Primary Examiner — Sheryl Lane*Assistant Examiner* — Calvin E Vansant(74) *Attorney, Agent, or Firm* — Daniel J. Iden(57) **CLAIM**

The ornamental design for a three dimensional filter frame, as shown and described.

DESCRIPTION

FIG. 1 is a perspective view of showing the new design for a three dimensional filter frame.

FIG. 2 is a left side elevation view thereof;

FIG. 3 is a right side elevation view thereof;

FIG. 4 is a front elevation view thereof;

FIG. 5 is a back elevation view thereof;

FIG. 6 is a top plan view thereof; and,

FIG. 7 is a bottom plan view thereof.

Broken lines in the drawings provide environmental structure and form no part of the design to be patented.
